UNITED STATES PATENT OFFICE.

WILLIAM B. SHAW, OF BROOKLYN, NEW YORK.

DESIGN FOR A HASSOCK.

SPECIFICATION forming part of Design No. 25,823, dated July 21, 1896.

Application filed April 8, 1896. Serial No. 586,754. Term of patent 7 years.

To all whom it may concern:

Be it known that I, WILLIAM B. SHAW, a citizen of the United States, residing at Brooklyn, in the county of Kings and State of New York, have invented and produced a new and original Design for Hassocks, of which the following is a full, clear, and exact description.

The top of the hassock is of stellated form, as at A, and the sides B are of a corresponding shape, forming a sharply-defined edge at the juncture with the top, the points of the sides meeting those of the top. The upper star-surface is divided into a number of pentagonal figures C, their contracted bases be-

ing arranged around the central figure D, and each pentagonal figure is given more or less of a convexed upper surface. The undulations of the sides of the hassock closely follow the undulating edges of the top of the hassock, and at opposite sides of the hassock tabs E appear as extending from the top.

I claim—

The design for a hassock herein shown and described.

WILLIAM B. SHAW.
